US0D1025162S

(12) **United States Design Patent** (10) Patent No.: **US D1,025,162 S**
 Park (45) Date of Patent: ** Apr. 30, 2024

(54) **ROBOT FOR SERVICE**

(71) Applicants: **HYUNDAI MOTOR COMPANY**, Seoul (KR); **Kia Corporation**, Seoul (KR)

(72) Inventor: **Tae Eon Park**, Hwaseong-si (KR)

(**) Term: **15 Years**

(21) Appl. No.: **35/517,157**

(22) Filed: **Apr. 28, 2023**

(80) **Hague Agreement Data**

Int. Filing Date: **Apr. 28, 2023**

Int. Reg. No.: **DM/228638**

Int. Reg. Date: **Apr. 28, 2023**

Int. Reg. Pub. Date: **May 12, 2023**

(30) **Foreign Application Priority Data**

Nov. 4, 2022 (KR) 30-2022-0045368

FOREIGN PATENT DOCUMENTS

CN 308250987 * 9/2023

Primary Examiner — Patricia A Palasik

(57) **CLAIM**

The ornamental design for a robot for service, as shown and described.

DESCRIPTION

1. Robot for service

1.1 : Perspective

1.2 : Front

1.3 : Back

1.4 : Left

1.5 : Right

1.6 : Top

1.7 : Bottom

Reproduction 1.1 is a perspective view of a robot for service showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof.

1 Claim, 7 Drawing Sheets
